UNITED STATES PATENT OFFICE

146,651

DESIGN FOR A BROOCH

Frank J. Gargano, Providence, R. I.

Application May 13, 1946, Serial No. 129,656

Term of patent 3½ years

(CL. D45—19)

To all whom it may concern:

Be it known that I, Frank J. Gargano, a citizen of the United States, residing at Providence, in the county of Providence and State of Rhode Island, have invented a new, original, and ornamental Design for a Brooch, of which the following is a specification, reference being had to the accompanying drawing, forming part thereof.

Fig. 1 is a plan view of a brooch, showing my new design; and

Fig. 2 is an edge view of the same.

I claim:

The ornamental design for a brooch, as shown.

FRANK J. GARGANO.
